(57) **CLAIM**

The ornamental design for a support for fishing equipment as shown and described.

DESCRIPTION

1. Support for fishing equipment

1.1 : Perspective

1.2 : Perspective

1.3 : Front

1.4 : Back

1.5 : Left

1.6 : Right

1.7 : Top

1.8 : Bottom

The support for fishing equipment is used for linking fishing rod holders, cameras, or cutting boards on ships.

The broken lines in the drawings depict portions of the support for fishing equipment that form no part of the claimed design.

1 Claim, 8 Drawing Sheets
